Assistant Examiner — Laura H Yu

CLAIM

The ornamental design for a multi-functional triangular bookrest, as shown and described.

DESCRIPTION

FIG. 1 is a front elevation view of a multi-functional triangular bookrest showing my new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the multi-functional triangular bookrest in a folded position.

1 Claim, 9 Drawing Sheets
